VEHICLE FLOOR MAT

James H. Barnes, Wadsworth, Ohio

Application November 8, 1955, Serial No. 38,788

Term of patent 14 years

(Cl. D9—6)

Fig. 1 is a plan of the vehicle floor mat of the invention; and

Figs. 2 and 3 are enlarged vertical sections on lines 2—2; and 3—3, respectively, of Fig. 1.

The characteristic features of my design for the vehicle floor mat reside in the upper portions thereof having the configuration and pattern shown.

I claim:

The ornamental design for a vehicle floor mat, as shown and described.
